(57) CLAIM

The ornamental design for a sports cap handbag, as shown and described.

DESCRIPTION

FIG. 1 is a top front perspective view of a sports cap handbag showing my new design;

FIG. 2 is a left elevation view, with the right elevation view being a mirror image thereof;

FIG. 3 is a front elevation view thereof;

FIG. 4 is a rear elevation view thereof;

FIG. 5 is a top plan view thereof; and,

FIG. 6 is a bottom plan view thereof.

The broken lines shown in the drawings illustrate portions of the sports cap handbag that form no part of the claimed design.
